CLAIM

The Ornamental design for a combined air purifier and surface sanitizer, as shown and described.

DESCRIPTION

FIG. 1 is a top perspective view of the combined air purifier and surface sanitizer showing our new design;

FIG. 2 is bottom perspective view thereof;

FIG. 3 is a back view thereof;

FIG. 4 is a front view thereof;

FIG. 5 is a first side view thereof;

FIG. 6 is a second side view thereof;

FIG. 7 is a top plan view thereof; and,

FIG. 8 is a bottom plan view thereof.

The broken lines shown in the figures depict portions of the combined air purifier and surface sanitizer that form no part of the claimed design.

1 Claim, 8 Drawing Sheets
